WINDING REEL

Lavern J. Jordan, Fairview Village, Ohio, assignor
to Industrial Rayon Corporation, Cleveland,
Ohio, a corporation of Delaware

Application December 27, 1938, Serial No. 247,813

15 Claims. (Cl. 242—53)

This invention relates to winding reels of the type which, during rotation thereof, continuously wind strip material thereon, advance it lengthwise thereof in a plurality of generally helical turns, and unwind it therefrom. The winding reels of the present invention find commercial application in a variety of ways. They may, for example, be employed to advantage for continuously but temporarily storing in a small, compact space any suitable strip material, such as thread, ribbons, films, artificial horsehair, artificial straw, bundles of filaments, etc., all of which are for convenience referred to hereinafter as "thread."

The reels illustrated as embodying the invention, which are of relatively large diameter, are applicable to the manufacture of fibers of staple length by a continuous process performed on apparatus of the type shown, described and claimed in application Serial No. 144,582, filed May 25, 1937, by Hayden B. Kline and Lavern J. Jordan. In said apparatus threads consisting of thousands of filaments are formed, continuously but temporarily stored on a series of reels, and subjected to any desired processing media, after which the filaments are severed into fibers. Reels of relatively large size are required because of the fact that the large threads require considerable space on the reels and hence the pitch of the helices formed by the reels must be large in order to prevent overlapping of the adjacent threads.

Reels of the type with which the present invention is concerned are particularly well adapted for such use since, even when of large size, they are relatively light in weight, of low cost, and operate at a minimum power consumption. It will be understood, of course, that while the invention will be disclosed hereinafter in connection with reels particularly adapted to the manufacture of fibers of staple length, reels embodying the invention may be employed for numerous other uses.

In the drawings, Figure 1 illustrates a plan view of a reel embodying the present invention, together with its associated supporting and driving apparatus. Figure 2 is a front elevation of the reel from line 2—2 of Figure 1. Figure 3 is a sectional elevation through said reel from line 3—3 of Figure 2, certain parts of the reel beyond the section being omitted for the sake of clearness. Figure 4 is an elevation of an individual bar member forming part of the driving reel member. Figure 5 is an elevation of an individual bar member forming part of the driven reel member. Figure 6 is an elevation on the same

scale as the preceding figures depicting a portion of one reel member but embodying other means for holding the bar members in place on the supporting members. Figure 7 is an elevation of an individual bar member adapted to be mounted as shown in Figure 6.

Figure 8 is an end elevation from line 8—8 of Figure 9 of another form of reel embodying the invention. Figure 9 is a sectional elevation through said reel from line 9—9 of Figure 8, parts 10 of the reel beyond the section being omitted for the sake of clearness. Figure 10 is an elevation on an enlarged scale of the hub member on which are mounted the supporting members of the driving reel member. Figure 11 is an elevation on 15 the same scale as Figures 8 and 9 of an individual bar member forming part of the driving reel member. Figure 12 is a sectional elevation of said bar member on an enlarged scale from line 12—12 of Figure 11. Figure 13 is an elevation of the 20 inner supporting member for the bar members of the driving reel member. Figure 14 is a sectional elevation of the supporting member of Figure 13 from line 14—14 thereof. Figure 15 is an elevation of the inner supporting member for the bar 25 members of the driven reel.

In the drawings, like reference characters refer to like parts throughout.

By reference to Figures 1, 2, and 3, it can be seen that the reel of the first embodiment of the 30 invention is formed of two wholly rigid reel members 1 and 2 each of which is substantially circular in cross section. Each of said members is shown as of substantially cylindrical form, although they may, if desired, be of other forms; 35 e.g., frusto-conical. Reel member 1 has a periphery formed of longitudinally extending radially projecting bar members 3, while reel member 2 has a periphery made up of longitudinally extending radially projecting bar members 4, the bar 40 members of the two reel members being alternately disposed so that the two reel members occupy substantially the same space. Each of the reel members is mounted for rotation about its own individual axis, the axes of the two reel 45 members being inclined from parallelism with each other in a manner which causes thread wound about the reel members to advance lengthwise thereof during rotation of said reel members. In the illustrated embodiment of the invention, 50 the reel members are mounted for rotation about axes which are disposed in inclined relation to each other in parallel planes.

In the embodiment of the invention under discussion, driving reel member 1 is concentrically 55

mounted on and for rotation with a drive shaft 5 journalled in a frame member 6 which, as shown in Figure 1, is provided with a flange 7 by means of which it is mounted as by bolts 8 on the frame 5 of the apparatus as a whole. Reel member 1 may therefore for convenience be called the concentric reel member. The driven reel member 2 is mounted on said frame member 6 for rotation about an axis displaced as above described 10 from the axis of rotation of driving reel member 1, wherefore driven reel member 2 may be called the eccentric reel member.

On drive shaft 5 is mounted a helical gear 11 meshing with a helical gear 12 on shaft 13, which 15 may be rotated by any suitable means (not shown). The reel drive shaft 5 is rotatably supported in frame member 6 by means of spaced anti-friction bearings 14 and 15 which may conveniently take the form of ball bearings. The 20 outer race of the bearing 14 is located in frame member 6 against a shoulder 16 while the inner race of said bearing is positioned on drive shaft 5 on a finished portion 17, being located against shoulder 18. Thus bearing 14 is disposed between 25 shoulders 16 and 18.

Bearing 15, which is positioned at the supported end of frame member 6, is mounted with its inner race on finished portion 19 of drive shaft 5 while its outer race is located in a suitably finished bore 30 21 in frame member 6. A washer 22 is caused by means of a collar 24 located on drive shaft 5 to bear against the rear surface 23 of frame member 6. Thus drive shaft 5 is accurately located with respect to frame member 6 with the portion 35 25 thereof projecting from the unsupported end of frame member 6.

In the embodiment of the invention shown in Figures 1 to 5, inclusive, concentric reel member 1 comprises a hub portion 26 held on portion 40 25 of drive shaft 5 against a shoulder 27 on said drive shaft by means of cap nut 28 threaded on the end thereof. Positive driving engagement is provided by a pin 29 passing through said drive shaft which pin 29 engages a slot 30 at the rear 45 of said hub member. Spaced supporting members 31 and 32, which may, as shown, be of substantially circular disc-like form, are rigidly affixed to said hub member 26, as by bolts 33. Bar members 3 of concentric reel member 1 are 50 mounted in slots 34 on the peripheries of said supporting members 31 and 32, as shown in Figure 2. Said bar members, which are formed as in Figure 4, have a longitudinally extending portion 35 and a portion 36 extending radially toward the interior of the reel which latter portion is provided with shoulders 37 against which 55 said discs 31 and 32 bear.

Each of the bar members 3 is firmly fixed to 60 members 31 and 32 by means of taper pins 38 at at least one radial intersection of said bar members and each of members 31 or 32. Said pins serve to hold the bar members 3 firmly in said supporting members 31 and 32 and to prevent radial movement of said bar members with 65 respect to said discs. The holes for the pins 38 are preferably drilled and reamed in the initial assembly with the bar members in place. The bar members 3 are provided with such radially extending portions 36 and longitudinally extending 70 portions 35 in order that they may extend over and surround the supporting means for the bar members of the other reel member 2 without interference with the bar members or other parts of said other reel member.

75 In this embodiment of the invention, reel mem-

ber 2 is constructed similarly to reel member 1. It comprises internal and external spaced supporting members 39 and 40 which may be of substantially circular disc-like form provided with slots 34 in their peripheries, in which slots 5 are disposed the bar members of reel member 2. As in the case of bar members 3, each of said bar members 4 is provided with shoulders 37 against which bear supporting members 39 and 40. Each 10 comprises a longitudinally extending portion 38 and a radially extending portion 36 which permit the bar member to extend beyond the supporting means for bar members 3 of reel member 1. Bar members 4 are shown as held in supporting members 39 and 40 by means of pins 38 at the 15 radial intersections of said bar members and said supporting members in a manner similar to that described in connection with reel member 1.

As shown in Figure 3, the supporting members 39 and 40 are mounted on and spaced apart by a 20 cylindrical sleeve 41 which in effect forms the hub of reel member 2, the supporting members 39 and 40 being recessed as shown for the purpose of locating them with respect to said sleeve. The inner supporting member 39 terminates at 25 the interior bore of said sleeve for the purposes of assembly, while the outer supporting member 40 extends inward and serves to aid in locating the reel member 2 and the anti-friction bearing 42 by means of which the reel member 2 is 30 rotatably mounted on the frame member 6. Bolts 43 and nuts 44 spaced at intervals around reel member 2 serve to clamp the supporting members 39 and 40 together on the sleeve 41 and against shoulders 37 on bar members 4, thus 35 forming a rigid assembly of bar members 4, members 39 and 40, and sleeve 42. A tubular member 45 surrounding each bolt 43 may be provided to protect the bolts 43 from processing media and to aid in spacing the members 39 and 40.

In the embodiment of the invention shown in Figure 3, anti-friction bearing 42 comprises a roller bearing made up of an outer race 46 mounted in sleeve 41 and an inner race 47 mounted on a sleeve 48 fixed to frame member 6, rollers 49 45 being disposed between said races. Rings 50, shown as disposed at both ends of said rollers 49, may form parts of the cage for spacing said rollers. They may also serve to aid in sealing the bearing against the entrance of extraneous 50 materials such as the processing medium or against the escape of lubricant from the bearing itself.

Sleeve 48, to which is mounted the internal race 47 of the anti-friction bearing 42, and consequently reel member 2, is formed with an inner cylindrical surface by means of which it is journalled on a cooperating cylindrical surface of frame member 6. Said cylindrical surface on frame member 6 has its axis parallel to but offset from the axis of drive shaft 5. The external surface of sleeve 48 is likewise cylindrical, but its axis is inclined from parallelism with the axis of its internal bore, so that when the sleeve 48 is mounted in the intended position on frame member 6, the axis of its external cylindrical surface is disposed in inclined relation to the axis of drive shaft 5 but in a plane parallel to and offset therefrom.

Said sleeve 48 is rigidly fixed in the desired position on frame member 6 by means of screw 51. Disc-like member 52 is bolted to said sleeve 48 to hold the reel member 2 in position with respect to frame member 6 and also to protect the interior mechanism of the reel member. Reel 75

member 2 is thus located endwise on frame member 6 between shoulder 53 on sleeve 48 and member 52. If desired, a disc 54 may be mounted at the end of the reel member 2 and a sleeve of reagent-resistant material 55 may be mounted on the rear portion of sleeve 48 to protect the rear of the reel from possible attack by the processing liquid.

Various other means than those described above may be employed to hold the bar members of each reel member in the spaced supporting members thereof.

Thus the slots in the supporting members in which the bar members are disposed may be of such shape that the bar members fitting therein are prevented from radial movement. This may be accomplished by making the slot of enlarged cross section below the surface of the supporting member and forming the bar members so that they closely fit therein, whereby radial movement of the bar members with respect to the supporting members is eliminated. Thus in the embodiment shown in Figures 6 and 7, a dovetail arrangement is provided; that is, the slots 34' in each supporting member taper outward toward the bottom of the slot and the bar members 3' are provided with corresponding portions 56 which feed into said slots. Consequently, when each reel member is assembled, the supporting members are held against the shoulders 37 on the bar members while radial movement of the bar members with respect to the supporting members is prevented by the dovetail joint.

Each of the reels shown as embodying the invention is of cantilever form; that is, it is supported from one end only and has the other end thereof unsupported so that thread can be wound on or unwound over the end of the reel.

In general, the operation of the reel is similar to that of the reel shown, described, and claimed in copending application Serial No. 652,089 for "Winding reel," filed January 16, 1933, by Walter F. Knebusch. The offset relation of the reel members causes the thread wound about the reel to be carried for half the circumference of the reel by the bar members of each set; that is, for one-half a revolution of the reel, the bar members of one reel member carry the thread, while for the other half of the revolution of the reel the bar members of the other reel member carry the thread. Thus as the reel rotates the thread is transferred from the bar members of one reel member to those of the other. The inclined relation of the bar members causes the thread to advance lengthwise of the reel, this because of the fact that the thread winding on each reel member from the other reel member travels at right angles to the axis of rotation of the reel member to which it passes.

The result of these operations is to advance the thread lengthwise of the reel in a plurality of substantially helical turns the pitch of which is determined by the inclination of the axes between the reel members. In the reel of Figures 1 to 5, inclusive, for the direction of rotation indicated by the arrow in Figure 2, the thread will advance toward the unsupported end of the reel. This is advantageous since thus the benefits of the cantilever construction of the reel can be utilized to the fullest extent.

The reel of the embodiment of the invention shown in Figures 8 to 15, inclusive, is similar to that above described.

In this embodiment, the reel member 1a is mounted on drive shaft 5a which is journalled in

frame member 6a. The reel member 2a is rotatably mounted on frame member 6a, the axes of rotation of said two reel members being offset from and inclined to each other, as is the case in the previously described embodiment. Drive 5 shaft 5a is journalled in frame member 6a in anti-friction bearings; e. g., the ball bearings 14a and 15a. The outer race of ball bearing 14a is mounted in frame member 6a against shoulder 16a. The inner race of said bearing 14a is located on 10 drive shaft 5a against shoulder 18a. A collar 24a is mounted on drive shaft 5a to bear against the inner race of the other bearing 15a while the outer race bears against shoulder 57 in frame member 6a.

The drive shaft 5a, which is thus accurately located lengthwise of reel member 6a, may be driven by any suitable means such as a gear 11a.

Reel member 1a is mounted on the projecting portion 25a of drive shaft 5a. It comprises a hub 20 member 26a mounted on projecting portion 25a which is held thereon against a shoulder 21a on drive shaft 5a by means of a cap nut 28a threaded on the end of said drive shaft. Positive driving engagement is provided between said hub 25 member 26a and drive shaft 5a by a pin 29a passing through said drive shaft having its projecting portions disposed in a slot 30a in hub member 26a.

As in the previously described embodiment of 30 the invention, the bar members 3a of reel member 1a are supported by spaced supporting members 31a and 32a which are mounted on said hub member 26a. Said hub member, which is shown to advantage in Figure 10, is provided on its external surface with a plurality of recesses 58 engaged by corresponding lugs 59 on said supporting members 31a and 32a which are shown advantageously in Figure 13. Thus positive driving engagement is provided as between said hub 40 35 member 26a and supporting members 31a and 32a.

In this embodiment of the invention, the spaced supporting members 31a and 32a are clamped together by bolts 60 which are threaded at one 45 end into inner supporting member 32a and pass through outer supporting member 31a, being provided at their ends with cap nuts 61.

Tubes 62 of suitable material such as synthetic resin are provided around bolts 60 to protect 50 them from processing reagents. Washers 63, which may be made of rubber or like material, are disposed between the ends of said tubes 62 and the members 31a and 32a to aid in sealing the bolts against the entrance of processing 55 media. Similarly, cap nuts 61 which enclose the ends of bolts 60 may be made of or coated with suitable reagent-resistant material. Tubes 62 may, if desired, also assist in spacing the members 31a and 32a apart. It has been found desirable to dispose bolts 60 substantially as shown; that is, with a ring of said bolts near the hub 26a and another ring of bolts spaced therefrom near the bar members 3a.

As in the previously described embodiment of 65 the invention, the bar members 3a are disposed in slots 34a in the peripheries of members 31a and 32a, being rigidly held therein by means of pins 38a at the radial section of said slots and said bar members. The bar members 3a may be 70 shaped similarly to bar members 3 of the embodiment first described to permit them to extend beyond and surround the supporting means for the bar members 4a of the other reel member 2a. Such a shape is illustrated in Figures 11 75

and 12, the bar members thereof being provided with enlarged portions 64 at the points where they contact with supporting members 31a and 32a.

5 As shown in Figures 8, 9, 11 and 12, bar members 3a are provided with raised portions, such as the button-like portions 65, at the points where they come into contact with the bar members 4a of the other reel member. Similarly, bar members 4a are provided with raised portions 65. Such raised portions are for the purpose of avoiding wear on other portions of the bar members due to sliding contact during operation of the reel. While the button-like portions shown are 10 formed integral with the bar members, it is obvious that they may be separate from and be rigidly fixed by suitable means to the bar members.

15 Reel member 2a is formed somewhat similarly 20 to reel member 2 of the previously described embodiment of the invention.

25 Preferably, bar members 4a are mounted in slots 34a in supporting members 39a and 40a, pins 38a being provided to hold said bar members firmly to said supporting members. As in the case of reel member 1a, a series of spaced bolts 66 disposed about reel member 2a serves to clamp supporting members 39a and 40a together, said bolts being threaded into inner member 39a, 30 passing through outer member 40a, and being adapted to be tightened by means of cap nuts 61. Tubes 62 and washers 63 are provided to protect the bolts and to aid in spacing the members 39a and 40a, if desired. Reel members 39a and 40a 35 seat on hub sleeve 41a with sufficient pressure to hold them firmly on said sleeve. Supporting members 39a and 40a and sleeve 41a may be recessed as shown to aid in locating these portions in respect to each other.

40 Sleeve 41a is mounted for rotation about frame member 6a by means of anti-friction bearings 66 and 67; e. g., the ball bearings shown. These bearings are mounted on the external surface of frame member 6a in such a manner that the 45 axis of rotation of sleeve member 41a and consequently of reel member 2a is in the desired fixed offset and inclined relationship with respect to drive shaft 5a. Rear anti-friction bearing 67 is located endwise with respect to frame member 50 6a by means of a shoulder 68, while the other anti-friction bearing 66 is located endwise by means of a spacer sleeve 69 disposed between bearings 66 and 67. The outer race of bearing 66 is located against the shoulder 71 in sleeve 55 member 41a. Sleeve member 41a, and consequently reel member 2a, are thus located against movement endwise of frame member 6a by means of bearings 66 and 67 and by means of disc member 52a mounted on the unsupported end of 60 frame member 6a.

65 The rear portion of supporting member 40a may be formed with a sleeve portion 72 having one or more external fins 73 thereon to assist in preventing liquid from reaching the interior of the reel from the rear thereof.

70 As appears from Figure 9 and from Figures 13 to 15, inclusive, this embodiment of the invention includes means for preventing any processing liquid which may be applied to the reel from 75 reaching the interior mechanism thereof. Such means comprise a plurality of overlapping annular flanges disposed on the adjacent inner faces of the inner supporting members 32a and 39a of reel members 1a and 2a. Member 32a is provided with an annular flange portion 74 which

5 projects toward the supporting member 39a for reel member 2a. Reel member 39a is provided with a similar flange portion 75 which is directed toward supporting member 32a. Annular flange portion 74 is of smaller diameter than annular flange member 75; together, said annular flange portions effectively obstruct the space between the reel members 1a and 2a against the entrance of liquid.

10 Each flange portion may be substantially trough-shaped, as shown, to aid in preventing the passage of liquids. If liquid is applied to the thread on the reel, a large portion of any liquid which passes between reel members 1a and 2a is caught by the trough in annular flange portion 15 75 and is discharged between the bar members on the lower portion of the reel. Any liquid which is not caught by said annular portion 75 is caught by the trough in annular flange portion 20 74 and is discharged from the lower portion of 25 the reel. Since these portions overlap, they effectively prevent the entrance of any liquid to the interior of the reel. Said annular flange portion thus comprises a labyrinth seal. While only two such flange portions are shown, one for each reel member, it is obvious that a large number may be provided.

30 In this embodiment of the invention, the disc-like supporting member 31a is curved or dished, as shown in Figure 9, being disposed with its convex side toward the unsupported end of the reel. This is advantageous because it increases the strength of the member 31a and because it makes it possible to dispose the cap nuts 28a and 61 in recesses 76 formed in the face of the member 31a, 35 as shown in Figures 8 and 9. Therefore, no projections are provided at the unsupported end of the reel around which thread being discharged from the reel, can entangle as, for example, in the threading-up operation.

40 The reels above described are designed for operation over long periods during which they are subjected to processing liquids. For this reason, the bearings are enclosed for protection against the entrance of processing liquids and sealing means are provided between the reel members to prevent the passage of liquid therebetween. Moreover, parts of the reels exposed to the processing liquids may be made or covered with suitable reagent-resistant materials. Thus, the parts indicated in heavy sectioning, such as the bar members, the supporting members for said bar members, the hub members on which said supporting members are mounted, the tubes surrounding the through bolts which hold the supporting members together, the cap nuts therefor, etc., may be molded, cast, or cut of hard rubber, Bakelite, synthetic resins, or other materials 45 resistant to the action of the processing liquids.

50 As is apparent from the above description, reels embodying the present invention may be of very strong built-up constructions. This is particularly advantageous in the case of large reels, since it results in reductions in both cost and weight. Moreover, the reels of the present invention can be readily disassembled by removing the nut at the end of the drive shaft, drawing the concentric reel member off the drive shaft, and removing the member 52 or 52a from the 55 unsupported end of the frame member 6 or 6a preparatory to drawing the eccentric reel member off the frame member. Assembly of the reel may similarly be easily accomplished.

55 Furthermore, since in the illustrated embodiment

ments of the invention the reel members are mounted on anti-friction bearings, the power required to drive the reels is low, which is advantageous in plants for the continuous processing 5 of thread wherein large numbers of reels are employed. Such bearings reduce maintenance costs, since they may operate for long periods of time without getting out of order and without shutdowns for lubrication of the reels, adjustments for wear, etc. Indeed, it has been found 10 that if the anti-friction bearings are grease-packed at assembly, the reels will operate indefinitely with no attention to the bearings. Such advantages of anti-friction bearings are 15 provided by the present invention in a reel of cantilever construction, which feature is of far-reaching importance.

It is apparent that the embodiments of the 20 invention above described are purely illustrative and that numerous modifications may be made therein without departing from the spirit of the invention. It is evident that the reels of the invention may be employed for various other uses than those above indicated and in particular for 25 advancing strip materials other than thread. In the appended claims, the term "thread" is intended to include, besides thread, all materials capable of being wound and advanced by the 30 reels of the present invention. It is intended that the patent shall cover, by suitable expression in the appended claims, whatever features of patentable novelty reside in the invention.

What is claimed is:

35 1. A cantilever reel for advancing thread in a plurality of generally helical turns comprising a longitudinally extending supporting member which is supported from one end only; anti-friction bearing means mounted on the exterior surface of said supporting member; a first reel member comprising a rigid set of spaced, longitudinally extending bar members mounted on said anti-friction bearing means for rotation about said supporting member; a second reel member comprising a rigid set of spaced bar members alternating with those of said first reel member; and, supporting said second reel member for rotation thereof about an axis inclined from parallelism with that of said first reel member, anti-friction bearing means of an external diameter 40 smaller than the internal diameter of said first-mentioned anti-friction bearing means mounted in said supporting member within the limits of the portion of said first-mentioned reel member 45 associated with said first-mentioned anti-friction bearing means, one end of the structure defined by said reel members being unobstructed by supporting means for either reel member.

50 2. A cantilever reel for advancing thread in a plurality of generally helical turns comprising a longitudinally extending supporting member which is supported from one end only; anti-friction bearing means mounted on the exterior surface of said supporting member; a first reel member comprising a set of spaced longitudinally extending bar members mounted on said anti-friction bearing means for rotation about said supporting member; a second reel member comprising a set of spaced longitudinally extending 55 bar members alternating with those of said first reel member; a shaft having a projecting end on which said second reel member is mounted; and, supporting said shaft for rotation thereof about an axis inclined from parallelism with that of 60 said first reel member, anti-friction bearing means 65

of an external diameter smaller than the internal diameter of said first-mentioned anti-friction bearing means mounted in said supporting member within the limits of the portion of said first-mentioned reel member associated with said first-mentioned anti-friction bearing means, one end of the structure defined by said reel members being unobstructed by said shaft or said supporting member. 5

3. A cantilever reel for advancing thread in a 10 plurality of generally helical turns comprising a longitudinally extending supporting member which is supported from one end only; spaced anti-friction bearing means mounted on said supporting member, one of said antifriction bearing means being disposed adjacent the unsupported end of said supporting member; a first reel member comprising a set of spaced longitudinally extending bar members mounted on said spaced anti-friction bearing means for rotation about 15 said supporting member; a second reel member comprising a set of spaced longitudinally extending bar members alternating with those of said first reel member; a shaft having a projecting end on which said second reel member is mounted; and spaced anti-friction bearing means in said supporting member supporting said shaft for rotation thereof about an axis inclined from parallelism with that of said first reel member, one of 20 said last-mentioned anti-friction bearing means being of an external diameter smaller than the internal diameter of said first-mentioned anti-friction bearing means and being mounted in said supporting member adjacent the unsupported end 25 thereof, whereby one end of the structure defined by said reel members is unobstructed by said shaft or said supporting member. 30

4. A reel for advancing thread comprising two adjacent rigid reel members supported for rotation about axes which are inclined from parallelism with each other, each of said reel members including (a) two spaced supporting members extending transversely of their respective axes, (b) means extending from one of said supporting members to the other for maintaining said supporting members in spaced relationship and, rigidly fixed to the peripheries of said supporting members of said reel member, (c) a set of spaced, longitudinally extending bar members which project in one direction only from said supporting members to encompass the supporting members for the other reel member and which are interleaved with the bar members of the other reel member. 40

5. A reel for advancing thread comprising two adjacent rigid reel members supported for rotation about axes which are inclined from parallelism with each other, each of said reel members including (a) two spaced supporting members extending transversely of their respective axes 45 each of which has in its peripheral edge a plurality of recesses each of which in cross section is larger within than at the peripheral edge of said supporting member, (b) means extending from one of said supporting members to the other for maintaining said supporting members in spaced relationship, and (c) a set of spaced, longitudinally extending bar members having portions which closely fit the recesses in said supporting members, which bar members project in one direction only from said supporting members to encompass the supporting members for the other reel member and which are interleaved with the bar members of the other reel member. 50

6. A reel for advancing thread comprising two 55

adjacent rigid reel members supported for rotation about axes which are inclined from parallelism with each other, each of said reel members including (a) two spaced supporting members extending transversely of their respective axes and having radial slots in their peripheral edges, (b) means extending from one of said supporting members to the other for maintaining said supporting members in spaced relationship, (c) a set of spaced longitudinally extending bar members disposed in said slots, which bar members project in one direction only from said supporting members to encompass the supporting members for the other reel member and which are interleaved with the bar members of the other reel member, and (d) pins at the radial junctions of said slots and said bar members to prevent radial movement of said bar members in said slots.

7. A reel for advancing thread comprising two adjacent rigid reel members supported for rotation about axes which are inclined from parallelism with each other, each of said reel members including (a) two spaced supporting members extending transversely of their respective axes, (b) a common hub member on which said supporting members are mounted and, rigidly fixed to the peripheries of said supporting members of said reel member, (c) a set of spaced longitudinally extending bar members which project in one direction only from said supporting members to encompass the supporting members for the other reel member and which are interleaved with the bar members of the other reel member; and, in at least one of said reel members, through members extending from one supporting member to the other holding together the supporting members of said reel member.

8. A reel for advancing thread comprising two adjacent rigid reel members supported for rotation about axes which are inclined from parallelism with each other, each of said reel members including (a) two spaced, supporting members extending transversely of their respective axes each of which has in its peripheral edge a plurality of recesses each of which in cross section is larger within than at the peripheral edge of said supporting member, (b) a common hub member on which said spaced supporting members are mounted, and (c) a set of spaced longitudinally extending bar members having portions which closely fit the recesses in said supporting members, which bar members project in one direction only from said supporting members to encompass the supporting members for the other reel member and which are interleaved with the bar members of the other reel member; and, in at least one of said reel members, through members extending from one supporting member to the other holding together the supporting members of said other reel member.

9. A reel for advancing thread comprising two adjacent rigid reel members supported for rotation about axes which are inclined from parallelism with each other, each of said reel members including (a) two spaced supporting members extending transversely of their respective axes and having radial slots in their peripheries, (b) a common hub member on which said spaced supporting members are mounted, (c) a set of spaced longitudinally extending bar members which project in one direction only from said supporting members to encompass the supporting members for the other reel member and which are interleaved with the bar members of the other reel member, and (d) pins at the radial

junctions of said slots and said bar members to prevent radial movement of said bar members in said slots; and, in at least one of said reel members, through members extending from one supporting member to the other holding together the supporting members of said reel member.

10. A reel for advancing thread in a plurality of generally helical turns comprising two cooperating sets of bar members supported for rotation about axes which are displaced from each other, each of said sets of bar members being substantially circular in cross section; supporting means for each of said sets of bar members spaced from the supporting means for the other set of bar members; and, independent means on 15 adjacent faces of said supporting means cooperating to prevent the entrance of liquid, such as that applied to the thread on the reel for processing purposes, into the central portion of the space between the supporting means for said sets of bar members.

11. A reel for advancing thread in a plurality of generally helical turns comprising two cooperating sets of bar members supported for rotation about axes which are displaced from each other, 25 each of said sets of bar members being substantially circular in cross section; supporting means for each of said sets of bar members spaced from the supporting means for the other set of bar members; and, disposed on adjacent faces of said 30 supporting means, means which coact to form a labyrinth seal preventing the entrance of liquid, such as that applied to the thread on the reel for processing purposes, into the central portion of the space between the supporting means for said 35 sets of bar members.

12. A reel for advancing thread in a plurality of generally helical turns comprising two cooperating sets of bar members supported for rotation about axes which are displaced from each other, 40 each of said sets of bar members being substantially circular in cross section; supporting means for each of said sets of bar members spaced from the supporting means for the other set of bar members; and, disposed on adjacent faces of said 45 supporting means, overlapping annular ridges which cooperate to prevent the entrance of liquid, such as that applied to the thread on the reel for processing purposes, into the central portion of the space between the supporting means for said 50 sets of bar members.

13. A reel for advancing thread in a plurality of generally helical turns comprising two cooperating sets of bar members supported for rotation about axes which are displaced from each other, 55 each of said sets of bar members being substantially circular in cross section; supporting means for each of said sets of bar members arranged in spaced relation with respect to each other but with adjacent faces thereof being disposed in 60 close proximity; and overlapping trough-shaped annular ridges on said adjacent faces cooperating to prevent the entrance of liquid, such as that applied to the thread on the reel for processing purposes, into the central portion of the space between the supporting means for said sets of bar members.

14. A reel for advancing thread in a plurality of generally helical turns comprising two interdigitating sets of bar members mounted for rotation about independent axes which sets cooperate to advance thread lengthwise of the reel in a plurality of generally helical turns, and, mounted on the bar members of at least one of said sets, spacing means for preventing the bar members 70

spacing means for preventing the bar members 75

of said sets from coming into contact during rotation of said sets.

15. A reel for advancing thread in a plurality of generally helical turns comprising two interdigitating sets of bar members mounted for rotation about independent axes which sets coop-

erate to advance thread lengthwise of the reel in a plurality of generally helical turns, and, disposed on the bar members of at least one of said sets, projections adapted to contact with the bar members of the other set.
